UNITED STATES PATENT OFFICE

97,849

DESIGN FOR A DRESS

Abraham Greenspan, New York, N. Y.

Application November 8, 1935, Serial No. 59,444

Term of patent 3½ years

To all whom it may concern:

Be it known that I, Abraham Greenspan, a citizen of the United States of America, residing in Manhattan, county of New York, and State of New York, have invented a new, original, and ornamental Design for a Dress, of which the following is a specification, reference being had to the accompanying drawing, forming part thereof, wherein,

The circular elements on the front and back portions of the sleeves represent nailhead embroidery.

I claim:

The ornamental design for a dress, substantially as shown, and described.

ABRAHAM GREENSPAN.
